DESIGN FOR A COMPORT

Edwin W. Fuerst, Toledo, Ohio, assignor to Libbey
Glass Company, Toledo, Ohio, a corporation
of Ohio

Application January 26, 1940, Serial No. 89,715

Term of patent 14 years

To all whom it may concern:

Be it known that I, Edwin W. Fuerst, a citizen of the United States, residing at Toledo, in the county of Lucas and State of Ohio, have invented a new, original, and ornamental Design for a Comport, of which the following is a specification, reference being had to the accompanying drawing, forming a part thereof.

In the drawing:

Fig. 1 is a side elevational view of a comport showing my new design.

Fig. 2 is a top plan view thereof. The contour of the comport is symmetrical about a vertical axis.

I claim:

The ornamental design for a comport, substantially as shown and described.

EDWIN W. FUERST.
